UNITED STATES PATENT OFFICE

LAWRENCE E. BAER, OF ATTLEBORO, MASSACHUSETTS, ASSIGNOR TO THE BAER & CO
WILDE COMPANY, OF ATTLEBORO, MASSACHUSETTS

NECKTIE HOLDER

Application filed December 5, 1931. Serial No. 579,170.

This invention relates to necktie holders and the primary object of the invention is to provide a holder which is firmly and positively held in position against accidental movement and to also provide means for easily and quickly releasing the holder from its operative position thereby to enable like removal of the holder from the necktie and shirt.

10 Still further the invention aims to provide a necktie holder which has a movable jaw together with means for latching the jaw in operative position and to further and more specifically provide means which upon movement to unlatched position simultaneously effects movements of the jaw away from the shirt bosom, thereby to enable the device to be easily and quickly removed, and likewise applied.

20 Still further the invention aims to provide novel means for effectively clamping the holder against the shirt bosom and necktie.

The invention has further and other objects which will be later set forth and manifested 25 in the course of the following description;

In the drawing:

Figure 1 is a bottom plan view of the invention;

Figure 2 is a side elevation and

30 Figure 3 and Figure 4 are sections on lines 3—3 and 4—4 of Figure 1.

In proceeding in accordance with the present invention, a relatively stationary jaw 1 is provided which is formed of a piece of wire which is doubled upon itself to provide spaced parallel sides 2, the ends of the wire being curved inwardly and coiled to provide eyes 3, so that the jaw is of substantially J-shape in side elevation as shown in Figure 40 2. As herein shown the wire is preferably of the flat type, although round or other shaped types can be employed as desired.

The movable jaw 4 is also formed of wire which is doubled upon itself to form a loop having a straight end upon which a roller 6 is journaled for free rotation, the roller preferably having a corrugated or roughened periphery so as to more firmly grip the fabric. The sides 7 of the loop are curved downwardly so as to be disposed in substantially

the plane of the outer face of the jaw 1, and since the sides 7 are spaced outwardly from the sides 2 of the jaw 1 it will be seen that the fabric will be pinched by the sides 7 of the jaw 4 against the sides 2 of the jaw 1 and will thus be more freely held in position. The end portions of the wire of which the jaw 4 is formed are brought into abutting engagement with each other and are preferably

welded together to form an inclined arm 8 which latter is turned upwardly and bent to form an eye or knuckle 9 which latter receives pintles 10 that are formed integral with the curved ends of the jaw 1 whereby to provide pivotal mounting for the jaw 4.

A sleeve-like member 11 is mounted on the arm 8 and has a curved finger 12 secured to its inner end. For the purpose of latching the jaw 4 in operative position, a lever 13 is provided which is of substantially S-shape

60 and has one end 14 formed to provide a finger grip while its opposite end is bifurcated and has a roller 15 journaled between the furcations. The lever 13 is formed with oppositely disposed pintles 16 which latter are received

65 in the eyes or knuckles 3 whereby to pivotally support the lever.

In operation with the parts in the position of Figure 2 it will be seen that due to the resilient nature of the material of which the jaw 7 is formed, the roller 15 upon swinging of lever 13 engages against the arm 8 and depresses and holds the jaw 4 in its clamped position. To release the jaw 4 the lever 13

70 is swung to the dotted line position of Figure 2 wherein it will be noted that the roller 15 riding upwardly on the slightly inclined arm 8 engaged the curved finger 12 and upon continued movement of the lever 13, the roller 15 through the finger 12 causes the

75 jaw 4 to be swung about its pivot 10 away from the shirt bosom to the limit of its movement indicated in dotted lines, thereby enabling the holder to be easily and quickly

80 removed and likewise applied in position.

85 It will thus be seen that the necktie and shirt bosom are firmly gripped and the necktie held against accidental movement, and at the same time the holder is likewise held

90 against accidental movement.

95

100

Having thus described my invention what I claim as new and desire to secure by Letters Patent is:

1. A necktie holder including a substantially J-shaped jaw having spaced sides, a substantially O-shaped jaw having a roller at its outer end and an angular arm at its inner end, means to pivotally connect the arm to the inner end of the J-shaped jaw, a sleeve on the arm having a curved finger, and a substantially S-shaped cam lever pivoted to the inner end of the J-shaped jaw and having one end formed to ride on the arm to clamp the same in position and upon release to engage the curved finger so as to raise the pivoted jaw away from the other jaw.
2. A necktie holder including a substantially J-shaped jaw having spaced sides, a substantially O-shaped jaw having a roller at its outer end and an angular arm at its inner end, means to pivotally connect the arm to the inner end of the J-shaped jaw, a cam lever pivoted to the inner end of the J-shaped jaw and having a part to engage the arm to move same into clamping position and means carried by the arm for engagement with said part of the clamping lever whereby to move the O-shaped jaw away from the other jaw following release of the clamping action of the cam lever.
3. A necktie holder having a substantially J-shaped jaw, a movable jaw pivoted to the free end portion of the short arm of the J-shaped jaw, and a cam lever carried by said free end portion of the short arm of the J-shaped jaw to engage the movable jaw to move the latter to clamping position.
4. In a necktie holder, a substantially J-shaped jaw having spaced sides, a second jaw having an angular end pivoted in the space between the inner end portions of the sides of the first jaw and means also pivoted in the space between the inner ends of the sides of the first jaw and having a part to engage the angular end of the second jaw to move the latter to holding position.
5. In a necktie holder, a substantially J-shaped jaw having spaced sides, a second jaw having an angular end pivoted in the space between the inner end portions of the sides of the first jaw, a cam lever also pivoted in the space between the inner ends of the sides of the first jaw and having a part to engage the angular portion of the second jaw to move the latter to holding position.
6. In a necktie holder, a substantially J-shaped jaw having spaced sides, a second jaw having an angular end pivoted in the space between the inner end portions of the sides of the first jaw, a cam lever also pivoted in the space between the inner ends of the sides of the first jaw, and having a part to engage the angular portion of the second jaw to move the latter to holding position, and means carried by the second jaw to engage

said part of the cam lever upon release of the latter whereby to move the second jaw away from the first jaw.

7. In a necktie holder, a substantially J-shaped jaw having spaced sides, a second jaw having an angular end pivoted in the space between the inner end portions of the sides of the first jaw, a cam lever also pivoted in the space between the inner ends of the sides of the first jaw, having a part to engage the angular portion of the second jaw to move the latter to holding position, and a curved finger carried by the second jaw to engage said part of the cam lever upon release of the latter so as to move the second jaw away from the first jaw.

8. In a necktie holder, a substantially J-shaped jaw, a second jaw cooperating with the first named jaw and pivoted to the short arm of the first named jaw adjacent to the outer end of said short arm, and means connected to the free inner end portion of the short arm for engagement with the second jaw to move the latter to clamping position.

9. In a necktie holder, a substantially J-shaped jaw, a second jaw cooperating with the first named jaw and pivoted to the short arm of the first named jaw adjacent to the outer end of said short arm, and having a part spaced from the short arm and located between the latter and the adjacent portion of the long arm of the first named jaw, and means connected to the short arm and operable in said space between same and said part of the second jaw for moving the latter to clamping position.

10. In a necktie holder, a substantially J-shaped jaw, a second jaw cooperating with the first named jaw and pivoted to the short arm of the first named jaw adjacent to the outer end of said short arm, means pivoted to the free inner end portion of the short arm and engageable with the outer face of the adjacent part of the second jaw to move the latter to clamping position, and means carried by the second jaw and located beyond the free inner end of the short arm of the J-shaped jaw to be engaged by said pivoted means so as to be moved to inoperative position thereby.

11. In a necktie holder, a substantially J-shaped jaw, a second jaw cooperating with the first named jaw and pivoted to the short arm of the first named jaw adjacent to the outer end of said short arm, and having a camming part located between the long and short arms of the J-shaped jaw and spaced from the short arm, and a device pivoted to the free inner end of said short arm and engageable with the said camming part to move the second jaw to operative position.

In testimony whereof I have signed my name to this specification.
